[57] CLAIM

The ornamental design for an X-ray viewer, substantially as shown and described.

DESCRIPTION

FIG. 1 is a front perspective view of an X-ray viewer showing my new design;

FIG. 2 is a left side elevation view thereof with the undisclosed right side being identical to the left;

FIG. 3 is a front elevation view thereof;

FIG. 4 is a rear elevation view thereof;

FIG. 5 is a top plan view thereof;

FIG. 6 is a bottom plan view thereof; and

FIG. 7 is a front perspective view of a second embodiment thereof, the undisclosed right side being identical to the left, the rear being plain and flat, and the bottom being substantially similar to that shown in FIG. 6.
